DESIGN FOR A COMBINED BOTTLE AND STOPPER

Allen C. James, New York, N. Y.

Application May 26, 1936, Serial No. 62,835

Term of patent 3½ years

To all whom it may concern:

Be it known that I, Allen C. James, a citizen of the United States of America, residing in the borough of Manhattan, city of New York, county of New York, and State of New York, have invented a new, original, and ornamental Design for a Combined Bottle and Stopper, of which the following is a specification, reference being had to the accompanying drawing, forming part thereof, wherein,—

Figure 1 is a front view of a combined bottle and stopper showing my new design.

Figure 2 is a side view of the combined bottle and stopper shown in Figure 1.

Figure 3 is an elevational view of the stopper portion of the bottle.

Figure 4 is a sectional view of the bottle, taken along the line 4—4 of Figure 1, looking in the direction of the arrows.

I claim:

The ornamental design for a combined bottle and stopper, substantially as shown and described.

ALLEN C. JAMES.
